UNITED STATES PATENT OFFICE.

HENRY B. MORRIS, OF GENEVA, ASSIGNOR TO THE AUTOPHONE COMPANY,
OF ITHACA, NEW YORK.

MACHINE FOR PREPARING MUSIC-ROLLERS.

SPECIFICATION forming part of Letters Patent No. 442,180, dated December 9, 1890.

Application filed May 2, 1890, Serial No. 350,372. (No model.)

To all whom it may concern:

Be it known that I, HENRY B. MORRIS, a citizen of the United States, residing at Geneva, in the county of Ontario and State of New York, have invented a certain new and useful Machine for Preparing Music-Rollers, of which the following is a full, clear, and exact description, which will enable others skilled in the art to which it appertains to construct and use the same, reference being had to the accompanying drawings, which form a part of this specification.

This invention relates to the construction of rollers to be used in connection with mechanical musical instruments in which the music is produced by means of elevations upon the surface of a slowly-turning cylinder, which engage with the keys or other sound-producing parts of the instrument.

The object of my invention is to provide means for cheaply and accurately clothing music-rollers previously prepared with the elevated points and surfaces which are to produce the music by winding narrow strips of sheet metal spirally around said rollers, said metallic strips being indented upon one edge to form the projecting playing points and surfaces.

My improved machine consists, first, of certain punches and dies automatically operated to cut away such portions of the edge of an advancing metallic strip as are not needed for music-playing projections; second, of feelers and levers arranged to engage with perforations in a pattern-roller or in a pattern-belt wrapped upon a cylinder and by their engagement with said perforations to actuate the cutting-punches, and, third, of means for winding the prepared metallic strip upon the music-roller so that the projecting surfaces shall be properly located thereon in accordance with the previously-prepared pattern-belt.

In order to fully explain my invention, I have illustrated the same with drawings, in which—

Figure 1 is a general view of my improved machine in front elevation. Fig. 2 is a side elevation, the standard B' being removed the better to display the working parts. Figs. 3,

4, and 5 are enlarged detail views of the clutch mechanism for governing the operation of the cutting-punches. Fig. 6 is a detail view of the punches and their corresponding dies. 55 Fig. 7 is a detail view of a portion of the pattern-roller, showing the forms and arrangement of the perforations in said pattern-roller; and Fig. 8 is a detail view of a music-roller, showing the manner of applying the indented 60 metallic strip to said roller.

I will describe my improved machine as arranged to prepare music-rollers in which the music projections are disposed along the convolutions of a spiral line.

The principal working parts of my improved machine are mounted upon a horizontal bed-plate A, which is conveniently supported by legs A'. Two standards B B' are erected upon the bed-plate at opposite sides of said plate. 70 In the upper portion of said standards a shaft C is horizontally journaled. I term this the "main shaft" of the machine. A driving-pulley may be attached to the main shaft at any convenient point for the purpose of receiving a driving-belt from a motor.

Upon the main shaft C two eccentrics D E are mounted, being fitted loosely upon said shaft, so that the shaft may turn freely through them without revolving them. Said 80 eccentrics are respectively provided with straps D' E', which are each furnished with a downwardly-projecting rod D² E². Said rods are pivoted, respectively, at their lower ends to the upper portions of two vertically-sliding 85 blocks D³ E³. Said sliding blocks are guided in their vertical movements in grooves suitably formed in a standard F, mounted on the bed-plate. To the lower ends of the blocks D³ E³ two punches D⁴ E⁴ are respectively attached, corresponding in form with two dies D⁵ E⁵, secured in the upper surface of the bed-plate.

The above-described parts are so arranged that when either of the eccentrics D E is revolved its corresponding block is made to descend, so that the punch attached thereto enters the corresponding die. The eccentrics when at rest are arranged to remain in the position of their highest throw, the punches 95 being thus normally withdrawn from the dies.

I will here remark that the eccentrics and

their connections above described are arranged to be operated independently of each other.

I will now describe the mechanism by which 5 the music-roller to be prepared is supported and fed.

A horizontal shaft G is mounted parallel with the main shaft in journals G' G², formed upon two of the legs A' near the lower portion of said legs. A rigid frame H is journaled upon shaft G, said frame consisting of three upright bars H' H² H³, rigidly joined together by a cross-bar H⁴. At the lower ends of bars H' H² H³ journals are formed, in which 10 shaft G is loosely fitted. The frame H is free to be oscillated on shaft G, but is prevented from sliding longitudinally by collars G³ G⁴, secured upon the shaft. Upon that portion of shaft G which passes through journal G² a 15 screw G⁵ is formed, a corresponding female screw being formed in the journal. When the shaft G is revolved by means hereinafter to be explained, it is caused by the operation of screw G⁵ to move longitudinally, carrying 20 with it the frame H, above described. In the upper portion of the frame H journals J J' are formed, in which a shaft K is journaled, being disposed parallel to shaft G. A cylindrical roller L is rigidly mounted on shaft K 25 between the journals J J'. This is termed the "pattern-roller," and will be more particularly described.

The shafts G and K are actuated as follows: A small pulley C' is mounted upon the 30 main shaft C, from which motion is transmitted to a larger pulley G⁶ upon shaft G through the medium of a belt C². Two sprocket-wheels are fixed, respectively, upon the shafts G and K. Said sprocket-wheels 35 are of equal diameters, and are connected together by a chain M², the shaft K being thereby caused to revolve synchronously with shaft G. A disk K' is rigidly attached to the end of shaft K adjoining the journal J. A 40 short pin K² projects horizontally from the center of disk K', and a similar pin K³ is eccentrically located in said disk, projecting therefrom parallel with the central pin K². In the upper part of the frame-bar H' a 45 screw N is arranged to screw horizontally in line with the shaft K. The blank music-roller O to be prepared is supported upon the screw N and pin K², which enter holes centrally formed in the ends of the roller. The 50 eccentric-pin K³ enters a corresponding hole in the adjoining end of the roller, thus causing said roller to be revolved synchronously with the pattern-roller L.

From the above description it is plain that 55 by the operation of the screw G⁵ the shaft G is caused to move longitudinally when revolved, and that as the frame H partakes of said longitudinal motion the course of the pattern-roller L and music-roller O will be a spiral one.

The central bar H² of the frame H is provided with a horizontally-projecting arm H⁵

near the lower end of said bar. A weight H⁶ is suspended from said arm in order to give the frame H a tendency to swing away from the bed-plate A, for reasons hereinafter to appear. The frame is prevented from swinging beyond a certain point by an arm H⁷, projecting downwardly from the arm H⁵ and resting normally upon the floor.

I will now describe the mechanism whereby the eccentrics D and E are actuated and governed.

Two closely-adjoining longitudinal grooves are formed in the main shaft C, extending 80 under the eccentrics D and E and being thence prolonged for a suitable distance toward the journal B'. Said grooves are semi-circular in form, and are filled by two clutch-bars P P'. Said clutch-bars are closely fitted 85 to the grooves in which they lie, their outer surfaces being formed to coincide in their normal positions with the cylindrical surface of the shaft C. The clutch-bar P extends along the main shaft under the eccentrics D 90 and E. The other clutch-bar P' extends under the eccentric E and not under D. Said clutch-bars are provided with arms P² P³ at their opposite ends, disposed at right angles with the axes of the clutch-bars and curved 95 inwardly toward shaft C. Said arms are actuated, when not otherwise restrained, to oscillate outwardly from shaft C by means of open spiral springs R placed between the arms and shaft. Said oscillation results in 100 partially revolving the corresponding clutch-bar. Keyways S are formed in each of the eccentrics D and E, by means of which said eccentrics may be engaged by the clutch-bars and caused to revolve with the shaft 105 C. Two horizontal bars T T', called the "feeler-bars," are centrally pivoted to a standard T², erected on the bed-plate A. Said feeler-bars extend from a point vertically under the main shaft to points above the pattern-roller L. Said feeler-bars are disposed in the 110 same vertical plane, the bar T being above bar T'. Bar T extends farther across the pattern-roller than bar T', and each feeler-bar is provided at its outer end with a downwardly- 115 projecting feeler-point T³ T⁴, said points being arranged to press upon the surface of the pattern-roller and to engage with perforations U U' formed therein. The particular arrangement of said feeler-points and perforations will be further described.

The inner ends of the feeler-bars T T' are pivoted, respectively, to two vertical sliding rods V V'. Said rods are guided near their lower ends by holes in the bed-plate, through 125 which they pass, and are pressed upward by springs V² V³, attached to the lower side of the bed-plate. Each of the vertical rods V V' is curved into a hook V⁶ at its upper end, said hooks embracing the shaft C and being 130 accurately fitted to said shaft for a short distance on the upper side of the shaft. Said hooks are longer vertically than the diameter of the shaft, so as to allow the rods V V'

to move vertically. The rods V V' are normally depressed, so that the hooks V⁶ are drawn tightly down upon the upper surface of the main shaft. That portion of each 5 clutch-bar lying under its corresponding hook is so formed that its outer surface coincides with the surface of the main shaft C. The object of this construction is to enable the hooks V⁶ to control the clutch-bars while they 10 are passing under said hooks, preventing them from turning in their seats and engaging with the eccentrics D or E. When one of the feeler-points T³ T⁴ encounters a perforation in the continuously-revolving pattern-roller L, 15 said point descends into said perforation, thereby causing the opposite end of the feeler-bar and the corresponding vertical rod V or V' to be elevated by means of the spring V² or V³. The hook V⁶ being thus raised 20 above the continuously-revolving main shaft, the corresponding clutch-bar P or P' is free to engage with the keyway S in its corresponding eccentric as soon as it arrives under said keyway. The clutch-bar effects said engagement by rocking in its seat, being so actuated by the spring R, already described. The eccentric so engaged revolves with the main shaft, operating one of the punches D⁴ E⁴. 25 Before the revolution of the eccentric is completed the vertical bar V or V' is depressed to its normal position by the operation of a cam W or W', fixed upon the main shaft, which engages with a laterally-projecting block V⁴ or V⁵, formed upon the bars V V', 30 respectively. The depression of the bar results in the elevation of the feeler-point and its release from engagement with the perforation in the pattern-roller L. I will here explain that while one of the feeler-points remains engaged with a perforation in the pattern-roller the continuous revolution of said 35 roller results in oscillating the frame H toward the bed-plate A and elevating the weight H⁶. As soon as said feeler-point is released from said engagement, the weight causes the frame to oscillate outwardly to its 40 normal position. When the cam W or W' has by its continued revolution released the vertical bar V or V' from its depressed position, 45 said bar is prevented from again rising by its feeler-point, which again bears upon the im-perforate portion of the surface of the pattern-roller L until it encounters another perforation. The outer end of the hook V⁶ is 50 beveled inwardly, so as to engage and return the clutch-bar to its normal position. The eccentric is thus disengaged from the main shaft and does not again revolve until the hook V⁶ has been again elevated and the 55 clutch-bar released, as above described. During the revolution of shaft C the clutch-bar is retained in its normal position by the eccentric which encircles it.

The clutch-bars above described are retained in their seats in the main shaft by a collar X, encircling said shaft. The portions 60 of the clutch-bars under said collar and that

part of clutch-bar P passing under the eccentric E are beveled away, so that said bars may oscillate freely under the collar and so 70 that bar P can never engage with eccentric E.

The music-roller O is previously prepared by cutting in its surface a shallow spiral groove O'. Said groove corresponds in width with the thickness of the sheet metal which 75 is to be wound therein. Said metal, in the form of a narrow strip Y, is led across the bed-plate, passing over the dies D⁵ and E⁵, its forward end being secured to the music-roller by nailing or otherwise. The strip Y is 80 narrowed for a distance corresponding to the distance of the dies from the roller, so that this part of the strip may be flush with the surface of the roller. The revolution of said roller results in drawing the strip Y forward 85 and winding it edgewise in the groove O'. The punch and die D⁴ and D⁵ are so formed and arranged as to cut away the metal from one edge of the strip Y for a considerable 90 distance at each stroke. Punch and die E⁴ and E⁵ are narrower and cut the metal away for a much shorter distance, so that by their operation points may be left closely adjoining each other on the edge of the strip Y. The object of this construction is to save time 95 by means of the wider punch and die D⁴ D⁵ when it is desired to narrow the strip continuously for a considerable distance.

In order to govern the operation of the respective punches D⁴ and E⁴, the feeler-point 100 T³, which governs the narrow punch E⁴, is made in the form of a cylindrical pin, arranged to enter the circular perforations U in the pattern-roller. The feeler-point T⁴, which governs the punch D⁴, consists of a 105 thin plate of metal resting upon the pattern-roller and arranged to enter slots U' in said roller. Said slots are narrower than the holes U and feeler-point T³, so that feeler-point T³ cannot enter said slots. The perforations U 110 U' are previously formed in the pattern-roller, being arranged to produce a music-roller adapted to play a certain tune. When it is desired to prepare rollers for another tune, the pattern-roller may be removed and another substituted.

I will here remark that the pattern-roller is arranged with slots U' in such positions that they cause the die D⁴ to narrow the strip Y after the music-roller is wound full, so as 120 to prepare that portion which passes the dies after filling the music-roller, narrowing it, ready for beginning a new music-roller.

The spiral groove O' is cut or sawed in the music-roller throughout its entire length; but 125 the music-points do not extend so far, there being a blank space at each end. The object of this is to avoid bending the music-points sidewise and splitting the thin wood between 130 the last turn of the spiral groove and the end of the roller. The narrowed end of the strip Y is, however, wound in this portion of the groove and extends beyond it, being nailed or otherwise secured to the end of the roller.

From the foregoing description it will be seen that the indentations upon the strip Y are formed in accordance with the previously-prepared pattern L and immediately thereafter wound upon the music-roller. This mode of operation obviates the difficulty that would exist if the strip were wholly prepared and then wound upon the roller—namely, that very slight differences in the diameters of the music-rollers would result in improperly placing the music-points, since, though several of them may be intended to play at once, they may be widely separated by the strip Y. By winding the strip upon the roller immediately after indenting said strip any material variation in the positions of the music-points is prevented.

I will further remark that music-rollers of different diameters may be prepared by the improved machine above described without altering the machine, pattern-rollers properly prepared being of course introduced.

For convenience in returning the frame H to its place of beginning, after a roller has been prepared, the nut G² may be made in two parts, so that it may be opened and the shaft G moved longitudinally through said nut.

That part of the strip Y passing over the dies D⁵ E⁵ may be led through a guide of any well-known form in order to prevent lateral motion of the strip, and also to hold said strip down upon the dies and bed-plate.

Having fully described my invention, I claim and desire to secure by Letters Patent—

1. A machine for preparing music-rollers organized with a revoluble perforated pattern-roller, feeler-points arranged to engage with the perforations in that pattern-roller, and reciprocating punches governed in their motions by those feelers and arranged to indent one edge of a strip of thin metal, all constructed and arranged to operate upon a music-roller, which latter is adapted to be revolved synchronously with the pattern-roller and to wind the indented metallic strip upon that music-roller, substantially as described.

2. In a machine for preparing music-rollers, the combination, substantially as and for the purposes set forth, of a revoluble pattern-roller, circular perforations U in the surface of that pattern-roller, a cylindrical feeler-point T³, arranged to engage those perforations, slots U', formed in the surface of the pattern-roller, and feeler T⁴, arranged to enter those slots, said slots being narrower than

the diameter of the cylindrical feeler-point T³, so that feeler-point T³ cannot enter said slots.

3. In a machine for preparing music-rollers, the combination, substantially as described, of the following elements: a revoluble pattern-roller, circular perforations in the surface of that pattern-roller, a cylindrical feeler-point arranged to engage those perforations, a small punch governed in its operation by that feeler-point and arranged to cut away a short notch from one edge of a strip of thin metal, means, substantially as set forth, for connecting said feeler-point and small punch, slots U', formed in the surface of the pattern-roller, a feeler arranged to engage with those slots, a larger punch governed in its operation by that feeler and arranged to cut away a long notch from the edge of said strip of metal, and means, substantially as set forth, for connecting said feeler and larger punch.

4. The combination, substantially as and for the purposes described, of a continuously-revoluble perforated pattern-roller, feelers 8 arranged to press upon that pattern-roller and to enter the perforations therein, and a pivoted frame arranged to support the pattern-roller and to be oscillated by the continuous revolution of the pattern-roller when 8 a feeler engages with a perforation in that roller.

5. The combination, substantially as and for the purposes described, of a continuously-revoluble perforated pattern-roller, feelers 9 arranged to press upon that pattern-roller and to enter the perforations therein, a pivoted frame arranged to support the pattern-roller and to be oscillated by the continuous revolution of the pattern-roller when a feeler 95 engages with a perforation in that roller, and a weight attached to the pivoted frame for returning that frame to its normal position when the feeler is disengaged from the perforation in the pattern-roller.

6. The combination, substantially as and for the purposes described, of the shaft G, oscillating frame H, pivoted on that shaft, pattern-roller L, journaled in that frame and revolved synchronously with shaft G, screw G⁵, 10 and nut G², said parts being arranged so that the pattern-roller is moved longitudinally during its revolution.
